THERMOSTAT

John S. Mears, Oswego, Oreg.

Application February 24, 1958, Serial No. 49,784

Term of patent 14 years

(Cl. D52—7)

Fig. 2.

Fig. 1.

Fig. 1 is a front elevation of a thermostat embodying my new design;

Fig. 2 is a side elevation thereof. The side not shown is substantially the same in appearance as the side shown.

I claim:

The ornamental design for a thermostat, as shown and described.
